MOVABLE SUPPORTING BASE FOR SOUND RECORD TAPE

Jacob M. Kuhlik, Brooklyn, N. Y., assignor to
Hattie B. Kuhlik, Brooklyn, N. Y.

Application October 15, 1943, Serial No. 506,443

2 Claims. (Cl. 274—11)

1.

This invention relates to sound recording and reproducing machines particularly of the type for recording on film bands.

An object of my invention is to provide a very simple and inexpensive machine of this kind that is reliable and positive in action.

Heretofore considerable difficulty has been experienced in attempting to make sound records in moving vehicles where the recording apparatus is subjected to all kinds of vibrations and motions and especially in airplanes due to the rocking, tilting, looping the loop and nose diving, whereby the relative positions of the various parts of the apparatus, particularly the stylus, become displaced and thereby interrupt and prevent recording.

It has also been found difficult to make and maintain proper tension between the stylus and traveling film.

Furthermore in the ordinary machines considerable time and effort are expended in mounting and demounting the reels for the purpose of reversing and interchanging the same on the spindles.

Difficulty has been encountered also in making more than one track on a film, especially on a narrow film band.

It is a primary object of my invention to provide a machine of this kind that is simple and inexpensive to manufacture and that is reliable and positive in action.

Another object is to eliminate any possibility of displacement of the stylus relative to the film band due to vibration, shocks and jars, etc.

A further object is to provide novel means whereby the tension between the stylus and film is readily adjusted.

A still further object is to simplify the manner of mounting the reels on the spindle whereby the reels can be mounted and demounted with a minimum of time and effort.

Still another object is to provide means for impressing at least two tracks on a narrow film, one track being on each side of its center line.

I accomplish the foregoing and other objects and advantages of my invention by mounting the sound unit in a fixed and immovable position on the frame of the machine and by pivotally mounting the support or base for the traveling film band close to the sound unit with means for locking the base against movement.

The base is arranged to swing to and from the stylus point for the purpose, in one position thereof, when swung downwardly to enable the insertion or removal of the stylus point or for

2.

removing or inserting the film between the base and unit and is adjustable to make proper contact between the stylus and the film, the base for this reason being constructed as a two-part member, one part of which is formed with a raceway thereon to guide the film and is made adjustable to regulate the contact between the film and the stylus point.

In order that the film and stylus are properly positioned for impressing tracks on the film on either side of its center line, the reels are suitably marked on the front and back faces thereof. The tracks are impressed on the film for substantially its entire length, only a small portion at each end being unimpressed. The reels are reversible and interchangeable from one spindle to the other and when the supply on the supply reel has advanced to the take-up reel and one track has been impressed on one side of the center line of the film, the reels are reversed and interchanged, that is, the supply reel is mounted on the take-up reel spindle and the take-up reel is mounted on the supply reel spindle. The film is then laced between the unit and base and is in position to be run in a reverse direction to be impressed with a second track on the opposite side of its center line.

The spindle ends and reel hubs are so constructed that the reel is readily slid onto the end of the spindle and then spun into operative position on the spindle in very quick time. The reel can be removed in the same quick manner.

Other objects and advantages of my invention will be set forth in the following description and accompanying drawings thereof, in which:

Fig. 1 is a front elevational view of a recording and reproducing machine embodying my invention.

Fig. 2 is a plan view of the machine of Fig. 1.

Fig. 3 is a front end view showing the support for the sound unit and the film supporting base.

Fig. 4 is an enlarged detail plan view of the film supporting base, parts being shown in section.

Fig. 5 is a front detail view of the base of Fig. 4, showing in dotted lines its inoperative position.

Fig. 6 is a view similar to Fig. 4 but with one part of the base removed, parts being shown in section.

Fig. 7 is a detail view of the part of the base removed from Fig. 6, parts being shown in section.

Fig. 8 is a detail sectional view showing the spindle and reel mounting.

As shown, the machine is of a conventional type and embodies a suitable supporting frame which

may be open for ready access to its working parts or enclosed in a cabinet, the latter in some cases being preferable to eliminate noise not intended for recording. The machine as constructed is very light in weight and its working parts, wherever possible, arranged to be firmly supported against looseness and vibration. As herein shown, the base plate 2, forming a part of the frame work, may be supplied with a threaded bushing 2', to clamp the machine to any suitable support where the machine is set up for use. The base 2, to which an upright plate 3, is secured, on the front of which a pair of reels, 4 and 5, are mounted on spindles, 6 and 7, the spindles rotatable in bearings, 8 and 9, one of which, as 6, is the take-up spindle and the other the supply reel spindle.

The motor M is supported on the rear of the plate 3, the shaft 10 of which extends through the plate 3. A pulley 10' is fixed on the shaft at the rear of the plate and drives the spring belt 6', for driving the pulley 6" and spindle 6. On the shaft 10 at the front of the plate 3, a film feed wheel 11 is mounted and fixed by a set screw, the shaft 10 passing through a bearing in the plate 3.

The shaft 10 of the motor it will be noted runs at a reduced speed by a reducing drive of the motor forming a part of the motor, to drive the shaft 10 and feed wheel at the proper speed.

The reel spindles are mounted as shown, the supply reel spindle 7 at the left and somewhat lower than the take-up spindle 6, at the right, of a fixed sound unit mounted above the reels and spindles about central thereof.

The unit, indicated at U, is supported on an angle bracket u', fixed to the plate 3, on the front end of the bracket in an angular position as shown and held by screw u'', in slotted holes of the bracket for slight lateral adjustment of the unit and stylus to proper position on the film, which is supported under the unit on a supporting base and there fixed against movement, whereby only the stylus thereof is adapted to vibrate, to record the impulses imparted thereto on the film or reproduce audibly the impulses thus recorded.

The film supporting base indicated at 12, may be constructed in various forms to accomplish the results here required without departing from the scope of the invention, namely, to operate with the unit and stylus thereof supported in a fixed position above the base to withstand the vibration it would be subjected to when used in airplanes or other moving conveyances.

While it may be desirable in some cases to impress only a single line track along the center of the film band with a fixed unit at said position, it is more particularly intended here to impress two line tracks one along each margin at the side of the film band and on the same face of the band and in so doing, rewinding the film is not necessary as would be the case of impressing a single line track. It is a feature, therefore, of my invention to impress the two line tracks for the following reasons: first, a saving of film to the amount of fifty per cent, second, smaller reels may be used, third, the rewinding of the film is not required thereby saving time, since it is only necessary after impressing the first line to remove both reels from the spindles without entirely removing the film from either reel and switch them around end to end with the film thereon, so the side marked "Front" on the reels will be entered on the spindles to be at the rear, and fourth, the recording continues losing only

the lapse of time in switching the reels on the spindles and re-lacing the film by lowering the film base to start impressing the second line as a continuation of the first line in a direction reverse to the first line.

The reels and spindles are both constructed in a novel manner to enable the quick removal and replacement of the reels on the spindles when applied and to be firmly attached against rattling and wobbling action thereon, this being accomplished by providing the reels at their centers in any desirable manner with a threaded bushing, 4', which protrudes at each side of the reels to form a shoulder, 4'', at each side, to engage with a shouldered portion such as a collar, 7', on the spindles, forward of which the spindle extends and having a left hand threaded portion, 7'', close to the collar on which the threaded reels from either side thereof engage the short length of thread on the spindles to be drawn to the shouldered collars. The spindles extending forward of the short threaded part without thread to support the reels at the front ends, and to readily lead them on the spindles and for requiring only a few turns to revolve them to their right position on the spindles.

The reels, marked "Front" and "Back," on the outside faces of the reels, as seen in Fig. 1, and when applied to the spindles as there shown, to start a recording operation are both positioned with the word "Front" forward. The reel 5, on the supply spindle 7, has the blank film thereon, is led from the top of the reel to be drawn forward to rotate the reel in clockwise direction downward and around a guide roller 9, and upward over the base 12, and again downward to partly encircle the feed wheel 11, to be there engaged by a pressure roller 13, and upward to be attached to the reel 4, on the take-up spindle 6, to the top side thereof and attached to the reel and by several extra windings to be driven in the same clockwise direction by the aforesaid spring belt 6.

The reel 5, now on spindle 7, with the film thereon, is free to unwind by feeding the film band forward and the reel is free to rotate with the spindle 7, except that this spindle is frictionally held against self-unwinding to prevent slack and runaway looseness of the film. For this purpose the spindle 7, has a pulley 22, fixed thereon, over which a short spring belt 22', is stretched, and a pulley 22" on the plate 3, which may be secured against rotation, that holds the reel under a suitable tension to prevent unrolling.

The presser roller 13, is mounted at one end of a rock lever 14, mounted on a rock shaft 15, passing through a bearing 16, in the frame, for a clamp arm 17 on the shaft, at the rear of the plate, to the end of which a spring 18 is hooked and to a pin 19, on the frame, to rock the shaft, and roller 13, to engage the film with the feed wheel. An upstanding extended part 20, of the rock lever 14, has a finger knob 21, by which the presser wheel is released from the feed wheel 11 and returned by the spring 18.

The film supporting base 12, heretofore referred to, as used with the fixed unit, which is particularly designed for use in airplanes, as will be understood, is as well adapted for general use, especially in the type of machines where a single line is impressed in the band, and in this particular and improved method wherein two line tracks are impressed, the first one along the margin at one side of the band, then without rewind-

ing the film, switch the reels on the spindles to impress the second line at the other side of the film band on the same face of a narrow film band.

Since the unit is rigidly supported to withstand vibrations in airplanes, the film supporting base 12, is likewise firmly supported and arranged to be locked in a work position, for operation of the advancing film band to travel over the base and under the stylus of the unit. The film supporting base 12, for this reason is constructed to be movable to and from the unit and stylus point, or for lacing the film band under the stylus.

While the base could be a single member, I prefer, however, to construct the base as shown as a two-part member, including the adjusting means thereof, as a complete unit applicable to its work position on the frame plate 3.

The base 12 includes a body portion 25, preferably of circular formation as viewed from the front, and is supported at one side thereof, under the unit, on a rock shaft 26, to rock in a bearing 27 of the frame plate 3, which shaft has an adjustable clamp arm 28 attached, by which the body portion is held in an idle position by a spring 29, fixed on the end of the arm and hooked on a pin 30, on the frame, to rock the body at the front end and downward against a stop pin 31, at the front of the frame, see Fig. 1 and Fig. 5. A spring controlled lock bolt 32, passing through the body, for a reduced end 32' thereof, to engage in a perforation 32'', in the frame, see Fig. 6, to lock the body to a work position, when the body is lifted, and to firmly hold and lock the body. The lock bolt is located in the body at the lower end thereof, and is provided with a finger grip button 33, at the forward end, by which the bolt is drawn forward to release the reduced end from the perforation in the frame, and the spring 29, on the clamp arm, will draw the body downward. The bore 34, in which the bolt slides in the body, is counterbored to a larger diameter to receive a spring 35, which engages a shouldered portion of the bore, and a threaded washer 36, on the bolt, between which the spring is compressed to draw the bolt forward to lock the body and when returning, the same body is shifted to its locked position by grasping the finger button 33, which is pushed upward until the bolt enters the perforation to again lock the base to work position.

The body is fixed to the shaft with a set screw 37, to rock with the shaft 26, and a large-headed screw 37', tapped in the end of the shaft 26, holds the body to position against the frame 3, by removing this screw and releasing the set screw 37, the body may be removed from the shaft without disturbing the shaft in its mounting.

The other member of the two-part base, indicated at 38, see Fig. 7, is of a semi-circular shape at its top to conform to the body, in which the film raceway 39 is formed, a flanged portion 39', integral with this part, between which and a movable flange 40, the film band is guided. This movable flange member is supported on the stems of two headed screws 41, that are located in spaced bores, which bores are counterbored as at 42, to receive springs 43, between threaded washers 44, on the end of the screws which draw the flange inward to yieldingly ride against the film at one side thereof when in the raceway, the raceway being of slightly less width than the film band, to hold the film when slight variation in its width occurs, as is often the case.

This raceway member is supported on a stud 45, fixed in the body member at the top side as at

46, where a part of the circular portion is cut from the front of the body to receive the race member, to the width thereof, and a portion at the side of this hub like part is cut away to the rear of the body, forming an even platform 47, around this upstanding part of the body in which the stud 45 is fixed and extends.

The raceway member is bored as at 48, at one end to rock on the stud 45, a pin 49, is driven in 10 the rear side of the raceway member adjacent the front end on which the end of a flat spring 50, attached to the body at the rear, which bears down on the pin 49, and a knurled threaded adjusting screw 51, threaded in the body extending 15 upward to engage the underside of the raceway member, which has a free limited movement upward and downward, controlled by the adjusting screw 51, and the spring 50, by which, when the film is in place on the raceway, the body locked 20 to its work position, the proper adjustment with the stylus by this adjusting screw may be regulated, the spring 50 being quite powerful, will readily hold the parts in their adjusted position, without danger of shifting, and thereby avoiding 25 all looseness of these parts while the machine is in action.

The operation of the invention has been referred to in what has been above said and it is believed the same will be entirely plain without 30 further description. Certain of the advantages of this invention have also been pointed out in what has been above said and others will be readily seen with further description.

I do not limit myself to the particular details 35 of construction which have been set forth in the foregoing specification and illustrated in the accompanying drawings, as the same refer to and set forth only certain embodiments of the invention and it is obvious that the same may be modified within the scope of the claims hereof without departing from the spirit and scope of the invention.

It will be noted from the foregoing that the 40 voice unit and base for the traveling film are fixed in operative position relative to each other and that the stylus will be maintained in operative engagement with the film under any and all conditions and cannot become displaced by vibration or shock.

It will also be noted that by reason of the novel 45 construction of the spindle and reel hub, the reel can be initially slid over the protruding unthreaded end of the spindle until the hub threads engage the threads on the spindle and then by spinning the reel it can be driven home to operative position on the spindle very quickly. The reel can be taken off of the spindle in the same 50 easy and quick manner.

The construction of the reels and spindles is 55 such that the reels are adapted to be reversed and interchanged on the spindles, and the relative position of the reels and stylus is such that the stylus engages the film at a point on one side of the center line of the film when the reels are on the spindles in either their front or reverse positions.

Having described my invention, I claim:

1. In a sound recording and reproducing machine, a stationary sound unit, a stylus supported by said sound unit, a two-part pivotal base for supporting a traveling film in operative position relative to said stylus, one of said parts being swingable relative to the other, means for locking 70 said base as a unit against movement when

in operative position relative to the stylus and a screw carried by the stationary part of the base engaging the swingable part for moving said latter part to and from the stylus to adjust the tension between the stylus and film.

2. In a sound recording and reproducing machine, a frame having a perforation, a sound unit fixed on said frame, a stylus supported by said sound unit, a two-part pivotal base for supporting a traveling film in operative position relative to said stylus, one part of said base being swingable relative to the other, a spring pressed bolt carried by said base and adapted to coact with said perforation to lock the base as a unit in operative position relative to the stylus and a screw carried by the stationary part of the base and engaging the swingable part for moving said

latter part to and from the stylus for adjusting the tension between the stylus and film.

JACOB M. KUHLIK.
